(57) **CLAIM**

The ornamental design for a safety medical lancet, as shown and described.

DESCRIPTION

FIG. 1 is a perspective view showing my new design for a safety medical lancet;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view of the safety medical lancet of this invention illustrating ready for lancing;

FIG. 9 is a cross-sectional view of the safety medical lancet of this invention; and,

FIG. 10 is a cross-sectional view of the safety medical lancet of this invention after having completed lancing, with the needle withdrawn into the lancet when the user presses the latch.

The features shown in broken lines depict environmental subject matter only and form no part of the claimed design.
